UNITED STATES PATENT OFFICE.

GEORGE JOSEPH MURRAY, OF ROCKAWAY BEACH, NEW YORK.

DESIGN FOR A STREET-LAMP.

41,303.

Specification for Design.

Patented Apr. 11, 1911.

Application filed January 27, 1910. Serial No. 540,464. Term of patent 3½ years.

To all whom it may concern:

Be it known that I, GEORGE JOSEPH MURRAY, a citizen of the United States of America, residing at Rockaway Beach, in the county of Queens and State of New York, have invented a new, original, and ornamental Design for Street-Lamps, of which the following is a specification.

Referring to the drawings forming part of this specification, I have shown my design for street lamp by a view in elevation.

The main features of my design are as follows: The ornamental base or pedestal having a rectangular panel appearing on one side thereof and an opening or slot in the

panel; a column rising from the base or pedestal and encircled by a band of color in strong contrast to the color of the column; and a globe of spherical or approximately spherical shape supported by the column and encircled by a band of color in strong contrast to the color of the globe.

I claim—

The ornamental design for a street lamp, as shown and described.

GEORGE JOSEPH MURRAY.
